UNITED STATES PATENT OFFICE.

JOHN W. OSBORNE, OF WINCHESTER, ILLINOIS, ASSIGNOR OF TWO-
THIRDS TO CHARLES SMITHSON AND SOL HAINSFURTHER, OF
WINCHESTER, ILLINOIS.

SHOE-POLISHING MACHINE.

No. 804,878.

Specification of Letters Patent.

Patented Nov. 21, 1905.

Application filed February 20, 1904. Serial No. 194,581.

To all whom it may concern:

Be it known that I, JOHN W. OSBORNE, a citizen of the United States, residing at Winchester, in the county of Scott and the State of Illinois, have invented a new and useful Shoe-Polishing Machine, of which the following is a specification.

This invention relates to a device for cleaning, blacking, and polishing shoes, and especially to the means employed for feeding to the blacking brush or dauber a paste blacking and liquid polisher.

The invention comprises a shaft having thereon a plurality of brushes, one of which is adapted to serve as a dauber and the others as cleaning and polishing brushes, of reservoirs arranged in a plane above the dauber, of discharge-pipes adapted to convey the contents of the reservoirs to the dauber, means for forcing the blacking, paste, or liquid from the reservoirs, and a shallow tray for spreading it over the dauber. The shaft can be driven in any desired manner, either by hand or motor power.

My invention also consists of the novel features of construction and combination of parts hereinafter described, particularly pointed out in the claim, and shown in the accompanying drawings, in which—

Figure 1 is a perspective view of my device. Fig. 2 is a vertical elevation. Fig. 3 is a detail view, partly in section and partly in elevation, showing the reservoirs, discharge-pipes, and spreader-plate. Fig. 4 is a detail sectional view on the line 4-4 of Fig. 2, the belt being omitted.

In the drawings, A represents a suitable base, on which is mounted an inclined standard A', which may be formed of gas-pipe and which carries an adjustable bracket B. This bracket is held in its adjusted position on the standard A' by means of a suitable bind-screw, and in the bracket-arms is journaled a horizontal shaft B'. Between the bracket-arms there is fixed on the shaft a pulley B'', and at one end of the shaft is arranged a brush C, having a cylindrical periphery and a semi-spherical face C', the brush being made of any suitable polishing material.

At the opposite end of the shaft B' is a cy-

lindrical brush or dauber E, carrying on its outer face or side a conical cleaning-brush E'. This brush may also be of any desired material and construction. The shaft may be rotated by power from any desired source. I have shown the device arranged to be operated by hand-power, a collar F being arranged adjacent the upper end of the standard, which collar has a stub-shaft projecting from it, on which is arranged a grooved wheel F', and a handle F'' is connected to the wheel. A belt G runs over the wheel and pulley B'.

A bracket or platform H is carried by the standard A' and extends over the dauber E. On this platform are mounted receptacles H' and H'', the receptacle H' containing a paste blacking and the receptacle H'' containing a liquid blacking. These receptacles or reservoirs are cylindrical, and arranged in each is a piston H', to which is attached a piston-rod H''.

Passing upwardly through the bracket or platform H is a pipe J, opening upwardly into the receptacle H' and carrying at its lower end a shallow tray J', into which the lower end of the pipe opens, the bottom of the tray being perforated. A discharge-pipe K, having a fine bore, extends from the bottom of the receptacle H' and opens on the upper surface of the plate J'. The piston-rod H'' work through a guide-bracket L and have suitable handles or hand-grasps at their upper ends. Downward pressure on these handles, or either of them, actuates the respective piston and forces from the receptacle a portion of its contents. The pasty blacking contained in the receptacle H' is forced through the pipe J into the tray J' and out through the perforations of the tray and spread on the dauber revolving beneath and in contact with it.

The more liquid mass contained in the receptacle H'' is forced through the pipe K and discharged on the tray J' and drips over the edge of the tray upon the dauber. The amount of liquid or paste fed from the receptacles can be regulated by the extent of downward movement of the pistons each time a new supply is forced out.

The further operation of the device will be obvious.

Having thus fully described my invention, what I claim as new, and desire to secure by Letters Patent, is—

A device of the kind described comprising
5 a shallow covered tray having a perforated bottom, a rotatable brush placed below the said tray, means for introducing under pressure a paste blacking into the said tray, and

means for discharging a liquid blacking upon the top of the said tray, as and for the purpose set forth.

JOHN W. OSBORNE.
